COMBINED BATHTUB AND SHOWER STALL

Clarence Lee Folden, Downers Grove, Ill., assignor to
Sears, Roebuck and Co., Chicago, Ill.

Filed Mar. 13, 1974, Ser. No. 450,664

Term of patent 14 years

Int. Cl. D23—02

U.S. Cl. D23—49

Fig. 1

Fig. 2

Fig. 3

Fig. 4

Fig. 5

Fig. 6

FIG. 1 is a front perspective view of a bathtub and wall enclosure showing my new design;

FIG. 2 is another front perspective view thereof;

FIG. 3 is a top plan view thereof, on an enlarged scale;

FIG. 4 is a top plan view thereof, on an enlarged scale, with the top removed for convenience of illustration;

FIG. 5 is a cross-sectional view thereof, on an enlarged scale, taken substantially on line 5—5 of FIG. 1;

FIG. 6 is a cross-sectional view thereof, taken substantially on line 6—6 of FIG. 3.

I claim:

The ornamental design for a combined bathtub and shower stall, as shown.
